(57) **CLAIM**

The ornamental design for an oral care implement, as shown and described.

DESCRIPTION

FIG. 1 is a perspective view of the new design;

FIG. 2 is a right side view thereof;

FIG. 3 is a left side view thereof;

FIG. 4 is a rear view thereof;

FIG. 5 is a front view thereof;

FIG. 6 is a top view thereof; and,

FIG. 7 is a bottom view thereof.

All broken lines shown in the drawings are directed to environment, wherein the two broken line ovals on the side of the article and the broken line circle on the bottom of the article are superimposed on a continuous surface. The broken lines form no part of the claimed design.

1 Claim, 4 Drawing Sheets
